UNITED STATES PATENT OFFICE.

J. EBEN ALMY, OF JAMESTOWN, NEW YORK.

IMPROVEMENT IN CARPET-RAG LOOPERS.

Specification forming part of Letters Patent No. **146,564**, dated January 20, 1874; application filed April 19, 1873.

To all whom it may concern:

Be it known that I, J. EBEN ALMY, of Jamestown, in the county of Chautauqua and State of New York, have invented certain new and useful Improvements in Combined Loopers for Carpet-Rags and Button-Hole Cutters, of which the following is a specification:

My invention relates to devices designed for use in fastening the ends of rags to prepare them for weaving into carpets, and for cutting button-holes; and my invention consists of a removable looping-knife provided with a biting-slit for the rag and a V-shaped end, in combination with a bed having a V-shaped supporting-socket for the knife in piercing and looping the rags, the said knife and the V-shaped socketed bed serving also to operate as a button-hole cutter, whereby the removable knife cuts and loops the rags when it is fixed, and ties the knot in drawing it away from the socket-seat, upon which the lapped rag ends are held by the thumb and finger—the device embracing three essential points, viz., first, a notch that will have a biting-gripe to fasten the rag firmly when once inserted into it, so that it will not give trouble during the remainder of the operation, and then readily disengage the same when the knot is tied; second, a blade which is permanent during the first part of the operation—that is, forming the slit and the loop—and is then seized and withdrawn from its socket to tie the knot by a single stretching out of the arm; and, third, a base or bed upon which to hold the looped rag while tying the knot, in the operation of which several movements of the hands are saved in tying the knot over a permanent blade, and all the trouble and loss of time in withdrawing the rags from the blade and then pulling them up to tie the knot.

In the accompanying drawings, Figure 1 represents a view in perspective of my invention, showing the two first steps in the operation of looping. Fig. 2 represents a similar view, showing the loop made, but not closed; and Fig. 3, a similar view, showing the knife withdrawn from its socket-support to form the tie by drawing the loop with the knife.

The lap-board or bed A has formed within

it a V-shaped socket, B, to receive the correspondingly-shaped end of the knife C, which is thus firmly held in a vertical position for slitting the rags and forming the loop, yet can be removed for making the tie. The two edges *a* and *b* of this V-shaped end may terminate in a blunt point, *c*, and the knife thereby be wholly supported upon the inclined sides of the socket-seat. The knife C has two cutting-edges, C', terminating in a point. On one side the cutting-edge projects at *d*, so as to relieve the rags from unnecessary tearing in pressing them toward the lap-board. On the other side is a notch, D, having an open mouth, *e*, and terminating in a narrow biting-slit, *f*, for holding the loose end of the rag by its sharp angle, and allowing it to be easily drawn out.

Referring to the drawings, the operation is as follows: In order to loop the loose rag E with the long or ball-rag F, and effect the tie, place the rag E tightly in the holding-slit *f* of the notch D, so that its free end shall hang down by the side of the knife on its opposite side, and the notch D at his right. Place or lap the end of the rag E over the end of the ball-rag F; press them both thus lapped upon and over the knife down upon the surface of the bed A; hold the fingers of the left hand upon the lapped ends of the rags at the left of the knife; seize the knife with the right hand and withdraw it, carrying with it the loose end of the rag E, and the loop is formed and the tie effected.

An eye in the blade, or a spring-catch on its side, may be substituted for the fastening-slit, or the latter may be made in different ways so long as it serves to bite the rag to the blade.

As a button-hole cutter, the device requires no adjusting or changing, and no skill in using. The open spear-shaped socket B in the bed A forms a gage, and limits the piercing of the knife through the material, which is simply placed upon the bed over the socket, and held thereon by the thumb and finger, stretching the fabric over the sides of the bed-piece, and with the blade inserted and held between the thumb and finger its cutting-edge is made to pierce the fabric, and, passing into the socket,

gage thereby the length of the cut, and in this way the rag-looper and button-hole cutter are combined and used.

Having thus described my invention, I claim—

The removable looper-knife C, provided with the biting-slit f and V-shaped end a b c, in combination with the bed A, having V-shaped supporting-socket B for the knife, said knife and the V-shaped socketed bed serving also to oper-

ate as a button-hole cutter, in the manner set forth.

In testimony whereof I have hereunto set my hand this 9th day of April, A. D. 1873, in the presence of two subscribing witnesses.

J. EBEN ALMY.
